United States Patent Office

Des. 223,152

Patented Mar. 21, 1972

223,152

BEVERAGE SERVING CART

Fred Kauffman, Philadelphia, Pa., and Donald C. Siverts,
Torrance, Calif., assignors to Hitco

Filed Oct. 30, 1970, Ser. No. 25,745

Term of patent 14 years

Int. Cl. D12—16

U.S. Cl. D14—3

FIG. 1 is a perspective view of a beverage serving cart, showing our new design;

FIG. 2 is a side elevational view showing the side opposite that seen in FIG. 1;

FIG. 3 is a top plan view; and

FIG. 4 is an end elevational view showing the end opposite that seen in FIG. 1.

We claim:

The ornamental design for a beverage serving cart, as shown.
